US0D1060721S

(12) **United States Design Patent** (10) **Patent No.:** **US D1,060,721 S**
(45) **Date of Patent:** **** Feb. 4, 2025**

(54) **SAMPLE COLLECTION TUBE**

(71) Applicant: **Amazon Technologies, Inc.**, Seattle, WA (US)

(72) Inventors: **Gururaj Govindasamy**, San Ramon, CA (US); **Jasmin B. Farshi**, San Jose, CA (US); **Brian Scott Carpenter**, Livermore, CA (US)

(73) Assignee: **Amazon Technologies, Inc.**, Seattle, WA (US)

(**) Term: **15 Years**

(21) Appl. No.: **29/880,048**

(22) Filed: **Jul. 17, 2023**

(51) LOC (15) Cl. **24-02**

(52) U.S. Cl.

USPC **D24/224**

(57) **CLAIM**

The ornamental design for a sample collection tube, as shown and described.

DESCRIPTION

FIG. 1 is a top, front, left-side perspective view of a sample collection tube;

FIG. 2 is a bottom, back, right-side perspective view thereof;

FIG. 3 is a front view thereof;

FIG. 4 is a back view thereof;

FIG. 5 is a right-side view thereof;

FIG. 6 is a left-side view thereof;

FIG. 7 is a top view thereof; and,

FIG. 8 is a bottom view thereof.

The dashed broken lines depict portions of the sample collection tube that form no part of the claimed design. The dot-dashed broken lines represent boundaries of the claimed design and form no part of the claimed design.

1 Claim, 8 Drawing Sheets
